EXTRACTOR REMOVING TOOL

Edward J. Schisler, Latrobe, Pa.

Application October 14, 1940, Serial No. 361,096

2 Claims. (Cl. 42—25)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a tool for initiating the removal of a cartridge extractor from a rifle bolt of the type shown in U. S. Patent 2,198,610.

The purpose of the invention is to provide a simple tool which may be conveniently applied to a rifle to initiate removal of the extractor while the bolt is in the gun so that the firing pin may be quickly removed and replaced.

The specific nature of the invention as well as other objects and advantages thereof will clearly appear from a description of a preferred embodiment as shown in the accompanying drawing in which:

Fig. 1 is a fragmentary view of a gun with the improved tool in position to remove the extractor;

Fig. 2 is a perspective view of the tool;

Fig. 3 is a view in side elevation of the head member of the tool, and,

Fig. 4 is a view in side elevation and partly in section of the guide member of the tool.

Referring to the drawing by characters of reference there is shown a portion of a semi-automatic rifle in which a breech bolt 5 is reciprocally mounted in a receiver 6 and is adapted to be partially rotated into and out of locked "in battery" position. The extractor 7 is formed with a trunnion 8 which is journaled transversely in the bolt and extends through a slot or groove 9 in the firing pin 10 to limit longitudinal movement of the firing pin as well as to restrain it against rotational displacement. The firing pin can only be removed from the bolt when the trunnion of the extractor is disengaged therefrom.

The tool for initiating removal of the extractor comprises a brass guide member and a steel head member. The guide member includes a cylindrical rod 11 which is adapted to enter the cartridge chamber of the barrel when the breech bolt has been retracted. A collar 12 on the rear end of the guide merges with the rod through a tapered shoulder 13 which is adapted to engage in the shallow bolt recess 14 in the barrel.

The steel head member is rotatably connected to the brass guide member in any suitable manner. A convenient connection consists in providing on the head member a stem 15 which is inserted in an axial recess 16 in the guide and which is formed with a peripheral groove 17 for receiving a pin 18 passing eccentrically through the

collar 12. The head member includes a collar 19 which abuts the collar 12 and carries a handle 20 whereby the tool is readily manipulated and the head member rotated with respect to the guide member. A reduced cylindrical knob or button 21 is formed on the rear of the collar 19 and simulates the base of a cartridge case. The button is shaped for engagement by the front of the breech bolt and has one side cut away as at 22 to avoid interference with the extractor.

A pin 23 is fixed in the collar 19 and has a reduced and shaped end 24 projecting rearwardly alongside of and beyond the button. The shaped end 24 of the pin is adapted to engage the under surface of the extractor 7.

In employing the tool the breech bolt 5 is retracted sufficiently to permit the tool to be placed in front of the bolt and to insert its rod 11 into the cartridge chamber of the barrel. The pin 24 bears such an angular relation to the handle 20 that it will be in proper position underneath the extractor when the handle is slightly to the right of vertical. The breech bolt is now eased forwardly into engagement with the tool and is thereby brought to rest a short distance out of battery. Upon rotating the handle to the left the pin 24 is angularly displaced and initiates withdrawal of the extractor from the breech bolt. The extractor is now lifted out, the rifle is inclined and the firing pin, which is no longer restrained by the trunnion of the extractor, falls out. When the firing pin has been replaced, the extractor is reassembled to the bolt and the tool removed.

35 I claim:

1. In a tool, a guide member adapted for chambering in a gun barrel, a head member rotatably engaging the guide member and having a rear end adapted for engagement with a breech bolt, a pin eccentrically carried by the head and projecting rearwardly for engagement with a removable element of the breech bolt, and a handle on the head member having a predetermined angular relation to the pin.

40 2. In a tool, a guide member adapted for chambering in a gun barrel, a head member rotatably engaging the guide member and having a rear end adapted for engagement with a breech bolt, a pin eccentrically carried by the head and projecting rearwardly for engagement with a removable element of the breech bolt, and a handle on the head member.

EDWARD J. SCHISLER.
